UNITED STATES PATENT OFFICE.

WILLIAM THOMAS BUCKINGHAM ROBERTS, OF LEICESTER, ENGLAND, ASSIGNOR TO
UNITED SHOE MACHINERY CORPORATION, OF PATERSON, NEW JERSEY, A COR-
PORATION OF NEW JERSEY.

ORNAMENTING SHOE UPPERS BY STEP-BY-STEP BRANDING.

Application filed August 14, 1923. Serial No. 657,387.

To all whom it may concern:

Be it known that I, WILLIAM T. B. ROBERTS, a subject of the King of England, residing at Leicester, in the county of Leicestershire, England, have invented certain Improvements in Ornamenting Shoe Uppers by Step-by-Step Branding, of which the following description, in connection with the accompanying drawings, is a specification, like reference characters on the drawings indicating like parts in the several figures.

This invention relates to apparatus for ornamenting leather or the like, and while it will be particularly described in its relation to the operation of ornamenting the marginal portions of boot or shoe uppers, such as toe caps, it should be understood that it is also applicable to the ornamenting of other portions of boot or shoe uppers and to other leather or like goods.

The margins of uppers are customarily ornamented by perforations but there are comparatively narrow limits to the designs which can be produced by punches in fibrous springy material such as upper leather if the pattern is to be definite, clean cut and not likely to fray or lose its character. Then again when perforating is adopted as the mode of ornamenting it is necessary that the perforations be backed by suitable material which usually involves over-lapping to a considerable degree the adjoining parts of uppers and entails a substantial consumption of leather purely for the sake of backing the holes in the perforated pattern.

Moreover when the upper is perforated it is correspondingly and very substantially weakened locally and if there is to be no undue distortion, let alone rupture, of the perforated part in consequence of the last- ing strains the perforated section has usually to be confined between rows of reinforcing stitching. The section of upper thus confined is however, especially if it be the margin of a toe cap, subject to much flexure during wear of the shoe and is apt to become unsightly because of the localized creasing and bulging which then may be set between the stitching lines and which may in the course of but a short while so chafe the perforated parts that the leather between adjacent perforations cracks and the shoe acquires a shabby appearance.

One object of the invention is to provide an improved machine which will overcome all these various disadvantages of ornamentation by perforation, said machine being arranged for ornamenting by embossing or branding, which produces the desired pattern without the upper being of necessity penetrated to any considerable degree.

In its illustrated form the invention is exemplified in a machine wherein the work is fed step-by-step automatically past a reciprocating heated patterned branding tool which in the course of successive reciprocations impresses the pattern into the work at successive points so as to form a band of ornamentation.

An important feature of the invention relates to the work supporting device whereby a uniform impression of the branding tool is insured. To this end a work supporting bed directly beneath the operating tool is resiliently held in a hemispherical bearing.

Other features of the invention reside in the novel arrangement of the work feeding mechanism. In the illustrated arrangement the work is fed by being grasped between a feed foot and the work support, both of which are laterally movable and are pivoted on a vertical axis to facilitate operation upon curved work.

The invention will be more fully understood from a consideration of the machine shown in the accompanying drawings, in which

Fig. 1 is a side elevation of a portion of a machine constructed in accordance with my invention;

Fig. 2 is a plan view of the edge gauge and a portion of the work feeding mechanism;

Fig. 3 is an end view partly in section showing the work supporting bed and the work feeding mechanism;

Fig. 4 is a side elevation, from the same position as that of Fig. 1, of the feed foot carrying mechanism; and

Fig. 5 is a plan view partly in section showing in detail the presser foot arrangement.

The invention is herein illustrated as embodied in a machine of the type shown in Letters Patent of the United States No. 640,426, granted Jan. 2, 1900, on the appli-

cation of C. P. Stanbon, to which reference is made for the illustration and description of those details of the operating mechanism which are not described herein. In 5 general the machine embodies a supporting frame 10 in which is mounted a power-driven cam shaft 12 which is preferably under the control of a one revolution clutch, and the forward end of the frame supports 10 a reciprocating plunger 14 actuated by a link 16 having a strap 18 embracing an eccentric on the end of the shaft 12.

The lower end of this tool carrying the plunger 14 differs from the construction 15 shown in the patent in that it is extended laterally at 20 and provided with a dove-tailed slot to allow for the insertion of the branding tool 22. This tool may conveniently be held in place by a latch 24 pressed toward the front of the machine by means of 20 a spring 26 and capable of being withdrawn by engagement with a lug 28. For the purpose of heating the tool an electric cartridge unit 30 is mounted in the lower end 20 of 25 the plunger 14 and may be supplied with electricity through the leads 32.

Rotation of the cam shaft 12 will, therefore, cause the branding tool to be reciprocated and to repeat its pattern at predetermined intervals in the work as the same is fed forward through the machine. The work feeding members comprise broadly upper and lower slides 40 and 60 which are provided with dove-tailed connections to the 30 frame of the machine to allow horizontal movement thereof across the front of the machine in the direction of the feeding movement of the work.

In the preferred embodiment of the machine the upper feeding member 40 is provided with a vertical bore in which there is mounted a sleeve 42 (Fig. 4) adjustably held in position by means of a nut 44, and this sleeve serves as a guide for a plunger 46 45 (Figs. 1 and 3) carrying at its lower end a feed foot 48. This feed foot is pivotally mounted on the plunger and is retained thereon by means of a screw 50 (Fig. 4), the lower limit of its movement being determined by means of set nuts 52. This feed foot has a four-way motion imparted to it by mechanism like that described in the Stanbon patent above referred to, and the feeding distance is adjustable in the manner 50 disclosed in that patent. A spring 54 normally presses the feed foot toward the work, and the plunger is lifted by cam-operated mechanism not herein shown but which is described in said Stanbon patent. Lateral movement of the slides 40 and 60 is secured as in said Stanbon patent by means of a cam-operated lever 70 pivoted on the frame of the machine and connected by links 72 and 74 to the upper and lower slides respectively. The feed foot 48 is arranged to de-

scend upon the work close to the branding tool, and for that purpose its lower end is inclined under the lower end 20 of the plunger 14 which carries the tool as shown in Fig. 3. In order that the pivoting of the feed foot 48 may not be impeded by any jamming action, said feed foot may also be connected to the upper end of the plunger 46 by means of a bar 80 rigidly connected at 82 to the upper portion of said feed foot and pivotally connected by a screw 85 to the upper end of the plunger. The pivotal freedom of the feed foot 48 allows work with curved edges to be fed easily past the branding tool while maintaining the work in contact with an edge gauge so as to keep the ornamentation at a constant distance from the edge of the work. This necessarily results in causing a lateral displacement of the line of feed and may be effected while the feed foot 48 is in contact with the work.

In order that, under such circumstances, the feed foot may be returned to its original position for the next feeding movement, shoulders 84 are provided on the upper end 90 of the feed foot adjacent to its pivotal connection to the plunger 46. Corresponding shoulders 86 are provided upon a block mounted in a bracket 88 rigidly attached to the frame of the machine. When the feed foot is returned to starting position, one or the other of these shoulders 84 will contact with the corresponding shoulder 86 during the latter part of the return movement and will turn the foot back to its original position before it descends to re-engage the work, as illustrated in Fig. 5.

The lower work feeding slide 60 is provided with a vertical bore to receive the shank 62 of a cup-shaped member 64, said shank being supported on a ball 61. Threaded into this cup is a sleeve 66 provided with a hemispherical recess to receive the correspondingly shaped part of a work supporting bed 68. The upper surface of the sleeve 66 is roughened the better to engage the work. The work supporting bed 68 is provided with a depending stem 71 which passes through a hole at the bottom of the hemispherical recess somewhat larger than the size of said stem, and a spring is mounted around this stem pressing against a collar at the lower end thereof and at its upper end against a washer seated against the end face of the shoulder surrounding the opening in the hemispherical recess. This arrangement allows free rotation in a horizontal plane of both the work supporting sleeve 66 and the bed 68 when the ornamentation is being made upon work having a curved edge. If the machine is operating on material of uneven thickness (for example, close to a folded edge) the hemispherical work supporting bed 68 can tilt in its seat to accommodate itself to the varying

thickness of the work and thus avoid any uneven marking of the work by the branding tool.

In the present machine an additional work-controlling member is provided in the form of a presser foot 90 which acts to hold the work stationary except while it is being fed. This foot 90 is formed upon the lower end of the lever 92 pivoted at 94 on the frame of the machine and normally held against the work by means of a spring 96 (Figs. 1 and 5). The lower end of the lever is guided between lugs 98 (Figs. 1 and 3) formed on the bracket 88, and a special cam 100 on the shaft 12 is arranged in position to engage the upper end of the lever 92 and lift the presser foot 90 from the work when the work is being fed forward. An additional lever 102 is connected to the usual manually operated finger piece 104 of the form described in said Stanbon patent, and said lever 102 is so arranged that actuation of the finger piece 104 to lift the feed foot 48 will also lift the presser foot 90 to allow the insertion of work into the machine.

An edge gauge 110 shown in Figs. 1 and 2 is provided to assist in guiding the work to the tool and to insure the placing of the ornamentalations at an even distance from the edge of the work. This gauge is formed upon the forward end of a plate 112 which is adjustably secured to the table 114 of the machine by a wing screw 116. The forward end of the edge gauge is provided with a spring finger 120 arranged to rest lightly upon the work to hold the work in contact with the work plate. The distance of the under side of the finger 120 from the work table may be adjusted, in accordance with the thickness of the work being operated upon, by actuation of a screw 122 threaded in a lug of the edge gauge supporting member 112. Adjustment of this screw after slackening the wing screw 116 will turn the member 112 about its rear edge 124 to raise or lower the finger 120.

In the operation of the machine, after the branding tool has been properly heated, the feed foot 48 and the presser foot 90 are lifted by the actuation of the finger piece 104 and the work inserted beneath the branding tool with its edge in contact with the edge gauge 110 and resting beneath the spring finger 120. When the machine is set in motion, the branding tool will be reciprocated and the work fed forward step-by-step in much the same manner as the work is fed in the machine of the Stanbon patent. Varying with the class of leather and the time during which and the pressure with which the hot tool remains on the work at each operation, there is obtained an ornamentation which may vary from a mere searing of the grain or the surface of the leather to a deeply burned-in and clearly defined im-

pression penetrating all but through the leather. This ornamentation will be repeated along a predetermined line, and the machine may be stopped by means of its one-revolution clutch at a definite point in the cycle of operations with the branding tool out of contact with the work and the feed foot 48 raised. If desired, the impression may be filled in, in color, by washing over the surface of the work with some suitable pigment or enamel, wiping off all the excess which remains on the surface of the work.

Having described my invention, what I claim as new and desire to secure by Letters Patent of the United States is:—

1. In a machine of the class described having a reciprocable branding tool, a work support provided with a fractional section located immediately beneath the tool, said section being mounted for tilting movement to compensate for variations in the thickness of the work to ensure an even action of the whole surface of the tool.

2. In a machine of the class described having a reciprocable branding tool, a work support having a fractional section located in the path of the tool which is mounted for tilting movement to compensate for variations in the thickness of the work to provide an even resistance to the pressure of the tool, and a spring arranged to return said tilting section to the plane of the balance of the work support.

3. In a machine of the class described having a reciprocable tool and a mechanism for feeding the work, said feeding mechanism including means for supporting the work movable back and forth in the direction of feed and comprising a section mounted in the path of the tool constructed and arranged to pivot substantially about the axis of the tool during the feeding movement of the work.

4. In a machine of the class described having a reciprocable tool, a work feeding mechanism comprising means for supporting the work including a divided fractional section located in the path of the tool, said section being constructed and arranged for movement laterally during the feeding movement of the work and said section being constructed for rotation in the plane of the work support during said feeding movement.

5. In a machine of the class described provided with feeding mechanism including a feed foot, a work support provided with a section located in cooperative relation to said foot which is constructed and arranged to rotate substantially in the plane of the work support to allow curved feeding movement of the work and to tilt about a plurality of axes substantially in the plane of the table to compensate for variations in the work.

6. In a machine of the class described having a reciprocable tool and a work support, feeding mechanism including a member movable in the plane of said work support, said member being constructed and arranged for rotation about an axis substantially parallel to the axis of the tool and to tilt about a plurality of axes substantially in the plane of the work support.
7. In a machine of the class described having feeding mechanism, said mechanism including a laterally movable work support provided with a hemispherical recess having an opening at its lower end, a hemispherical work supporting bed complementary to said recess and provided with a depending stem passing through and smaller than said opening, and resilient means surrounding said stem and bearing against the first-named work support constructed and arranged to maintain said second-named work supporting bed substantially in the plane of the first work support.
8. In a machine of the class described having work feeding mechanism comprising a feed foot adapted to be brought into and out of contact with the work, said feed foot being pivotally mounted with respect to said feeding mechanism, means constructed and arranged to co-operate with said feed foot at one limit of its path of movement for returning said feed foot to a predetermined position.
9. In a machine of the class described having means for intermittently operating upon a piece of work and means for intermittently feeding said work comprising a feed foot, said foot being pivotally mounted upon the feeding mechanism, a member located at one extreme of the path of movement of the feeding means constructed and arranged to co-operate with said foot to return the same to its original position whenever it reaches this limit of its feeding movement.
10. In a machine of the class described, intermittent means for operating upon a piece of work, mechanism for intermittently feeding said work comprising a reciprocable feeding member located beneath the work, co-operating feeding means located above the work, said first-named feeding means comprising a section constructed and arranged to turn about an axis substantially at right angles to the plane of the work.
11. In a machine of the class described, means for intermittently operating upon the work, and means for feeding the work comprising reciprocable members located above and below the work, each of said members being provided with a work-engaging member pivotally mounted for movement about an axis substantially at right angles to the plane of the work.
12. In a machine of the class described, work feeding means comprising a reciprocable member, supporting means mounted on said reciprocable member for vertical movement, substantially at right angles to the direction of reciprocation, a work engaging foot pivotally mounted upon the lower end of said supporting member, and a vertical brace rigidly connected at its lower end to said work engaging foot, and pivotally connected at its upper end to the vertically movable supporting means, said brace being constructed and arranged to assist in supporting said work engaging foot for free pivotal movement.
13. In a machine of the class described having a work supporting table, a work feeding mechanism comprising a slide mounted for reciprocation parallel to the plane of the table along the direction of the line of feed, a plunger carried by said slide arranged for movement toward and away from the work table, and a feed foot pivotally supported on said plunger extending laterally therefrom substantially in the direction of the line of feed.
14. In a machine of the class described having a work supporting table, a work feeding mechanism comprising a slide mounted for reciprocation parallel to the plane of the table along the direction of the line of feed, a plunger carried by said slide arranged for movement toward and away from the work table, a feed foot pivotally supported on said plunger extending laterally therefrom substantially in the direction of the line of feed, and means cooperating with said pivoted feed foot to return the same to its original position at the end of each feeding movement.
15. In a machine of the class described, feeding mechanism comprising a pivotally supported work engaging feed foot, said feed foot being provided with shoulders at either side of its pivotal axis and means rigidly supported upon said machine constructed and arranged to engage said shoulders at one limit of the feeding movement to return the feed foot to a predetermined position.
16. In a machine of the class described having feeding mechanism comprising a feed foot arranged intermittently to engage the upper surface of the work, and power-operated means for imparting a four-way motion to said feed foot, a work supporting table, and a presser foot resiliently engaging the upper surface of the work to hold it against the table, said power-operated means being constructed and arranged automatically to lift said presser foot during the feeding movement.
17. In a machine of the class described, an edge gauge provided with a resilient finger engaging the upper surface of the work, means for supporting said edge gauge com-

prising a member extending in angular relation to the length of said finger, means for clamping said supporting member in position, and a screw for rotating said supporting member about one edge to lift said resilient finger to accommodate pieces of work of different thickness.

18. In a machine of the class described having means for intermittently operating upon the work, work guiding and controlling mechanism comprising reciprocable feeding members located above and below the work and arranged to have pivoted move-

ment about an axis substantially at right angles to the plane of the work, and an edge guiding and controlling device comprising a gage member provided with a finger adapted to overhang the upper surface of the edge of the work, said guiding member having means for adjusting the level of the finger including means for rotating the guiding member about one edge.

In testimony whereof I have signed my name to this specification.

WILLIAM THOMAS BUCKINGHAM ROBERTS.
